UNITED STATES PATENT OFFICE

2,627,470

PACKAGE

Oscar E. Seifert, Chicago, Ill., assignor, by mesne assignments, to Voss Brothers Manufacturing Co., Davenport, Iowa, a corporation of Iowa

Application July 7, 1945, Serial No. 603,706

6 Claims. (Cl. 99—175)

1

The present invention relates to the banding of link-type sausages and other articles in continuously connected series, and is concerned particularly with the construction of the packaging structure involved.

In the new package—as in the one disclosed in my Patent No. 2,379,934—the sausages or other articles are banded, either individually or in compact units of two or more, and are continuously connected together side-by-side in a straight row by intervening webs, which webs are of greater extent than the distance between the sausages and hold the latter close together when the row is laid out in a flat condition while permitting them to be easily spread apart when the row is flexed whereby to facilitate access to the webs for effecting separation of the row at any one of the webs.

One of the objects of the invention is to provide an improved package of the type described in which the banding is effected easily, neatly and very inexpensively.

Another object of the invention is to provide such a package in which the banding is effected by means of a single strip of paper or other flexible material.

Still another object of the invention is to provide an improved method of forming such a package.

While the foregoing statements are indicative in a general way of the nature of the invention, other more specific objects and advantages will be apparent to those skilled in the art upon a full understanding of the construction and manner of formation of the new package.

One embodiment of the invention is presented herein by way of exemplification, but it will of course be appreciated that the invention is susceptible of incorporation in other forms coming equally within the scope of the appended claims.

In the accompanying drawings:

Fig. 1 is a perspective view of a package constructed in accordance with the invention;

Fig. 2 is a plan view of the package;

Fig. 3 is a longitudinal section through the package, with the same arranged in a flat condition, taken on the line 3—3 of Fig. 2;

Fig. 4 is a similar section through the package, with the same flexed to spread the sausages apart at the webs;

Fig. 5 is a transverse section through the package, taken on the line 5—5 of Fig. 2;

Fig. 6 is a perspective view of the package, showing the same but partly completed; and

2

Fig. 7 is a fragmentary plan view of a section of the strip used in making the package.

As will be observed in the drawings, the new package is shown applied to a number of link-type sausages 10. While the package is one that possesses many unique advantages as applied to sausages, it will of course be appreciated that the package is also adaptable to other articles.

The sausages in the package are arranged side-by-side in a row, are individually banded by loops 11 formed from a narrow strip 12 of flexible banding material, and are continuously connected together by webs 13 formed from the same strip of banding material.

When the package is laid out in a flat condition, as when resting in a box or when being displayed, the loops 11 about the sausages are positioned in substantial abutment with each other along the median plane of the package, as shown in Fig. 3, and the webs 13 which extend between the loops are disposed substantially in tangential relation to the lower portions of the loops more or less in the plane of the bottom of the package. This arrangement of the webs 13 permits the same to be relatively long and yet hold the sausages rather closely together. At the same time it permits the sausages to be spread apart rather widely to expose the webs 13, as shown in Fig. 4, thus enabling anyone of the webs to be easily grasped and torn crosswise, along perforations 14 which may be provided to facilitate separation of the sausages. When the webs are torn crosswise the loops 11 will remain intact about the sausages, providing attractive identifying bands on which trade-marks, ingredients or other data may be displayed.

In forming the package the strip 12 is looped about each of the sausages in succession, as shown in Fig. 6, with the strip preferably tucked partially in under each sausage at both sides of the same. Before each sausage is placed in position on the strip 12 a tongue 15 is cut in the strip, preferably in the center of the latter, and when the strip is curled about the sausage to form the loop 11 the tongue 15 is disposed beneath the sausage with the end 16 of the tongue projecting beyond the sausage. The strip 12 after encircling the sausage is brought down flatly against the end 16 of the tongue, and the web 13 is secured to the same, preferably by a heat-sealing operation, the strip 12 being coated with a thermoplastic adhesive for this purpose. Other forms of attachment might, however, be used.

The strip 12 before and after being curled

about each sausage is preferably abruptly creased at 17 and 18 to facilitate the formation of the loop. While a single tongue 15 at the center of the strip 12 is preferably employed, two laterally spaced tongues might instead be substituted, either within the margins of the strip or along such margins.

It will be appreciated from the foregoing description that the new package is one which can be produced rapidly at but little expense by 10 means of automatic machinery—the sausages 10 or other articles being fed one at a time to the strip 12 into positions against the previously banded sausage, and the tongues 15 being cut one at a time just prior to the positioning of each 15 sausage in proper relation to that sausage.

While the invention has been herein illustrated and described as involving the individual banding of single sausages or other articles, it is equally applicable to the banding of sausages or 20 other articles in pairs, as for example, small, easily packed breakfast-type link sausages, and the following claims are therefore to be understood in referring to a "sausage" or "article" as designating a unit which may consist either of a 25 single article or of two or more of the articles.

I claim:

1. As a new article of manufacture, a packaging structure by means of which a plurality of 30 articles are banded and connected together side-by-side in a row, said structure comprising a single continuous strip of banding material which 35 completely embraces each of the articles in turn, said strip being looped about one portion of each article and being provided with a cut-out tongue which extends about the remaining portion of 40 the article and is connected at its end with the strip at a point beyond the article.

2. As a new article of manufacture, a packaging structure by means of which a plurality of 40 link-type sausages are individually banded and connected together side-by-side in a straight row, said structure being constructed of flexible paper material and consisting of a series of loop 45 portions and a series of intervening web portions, the loop portions closely encircling the sausages and being disposed in the flat condition of the packaging structure with their sides in approximate abutment with each other and with 50 their bottoms spaced apart, and the intervening web portions being located below the approximately abutting sides of the loop portions adjacent the lower face of the packaging structure and being connected to the spaced apart bottoms of the loop portions, said loop and web portions being integrally formed from a single continuous 55 strip of the paper material which has portions thereof overlapped and secured to one another in a two-ply, side-by-side contacting relation over a substantial area in said web portions.

3. As a new article of manufacture, a packaging structure by means of which a plurality of link-type sausages are individually banded and connected together side-by-side in a straight row, said structure being constructed of flexible paper 60 material and consisting of a series of loop portions and a series of intervening web portions, the loop portions closely encircling the sausages and being disposed in the flat condition of the packaging structure with their sides in approximate abutment with each other and with their bottoms spaced apart, and the intervening web portions being located below the approximately 65 abutting sides of the loop portions adjacent the lower face of the packaging structure and being 70

connected to the spaced apart bottoms of the loop portions, said web portions being of substantial length and being so constructed as to tear crosswise when forcibly pulled apart without disrupting the loop portions, and said loop and web portions being integrally formed from a single continuous strip of the paper material which has portions thereof overlapped and secured to one another in a two-ply, side-by-side contacting relation over a substantial area in said web portions.

4. As a new article of manufacture, a packaging structure by means of which a plurality of articles are individually banded and connected together side-by-side in a straight row, said structure being constructed of a single strip of pliant sheet material and consisting of a series of loop portions and a series of intervening web portions, the loop portions closely encircling the articles and being disposed in the flat condition of the packaging structure with their sides in approximate abutment with each other and with their bottoms spaced apart, and the intervening web portions being located below the approximately abutting sides of the loop portions adjacent the lower face of the packaging structure and being connected to the spaced apart bottoms of the loop portions by portions of the strip which are overlapped on and secured to one another in a two-ply, side-by-side relationship over a substantial contacting area, said web portions being of substantial length and being so constructed as to tear crosswise when forcibly pulled apart without disrupting the loop portions.

5. As a new article of manufacture, a packaging structure by means of which a plurality of relatively elongated articles are banded and connected together in a row extending transversely of the length of said articles, said structure comprising a single continuous strip of flexible banding material embracing each of the articles in turn, said strip being looped about each article and overlapped on and connected to itself, and including a plurality of individual band portions 45 about said articles, tongues cut from the material of said band portions, and intervening web portions connecting said band portions and secured to said tongues.

6. As a new article of manufacture, a packaging structure by means of which a plurality of link-type sausages are banded and connected together side-by-side in a row, said structure comprising a single continuous strip of flexible paper which completely embraces each of the 55 sausages in turn, said strip being looped about each sausage and overlapped with and connected to itself over a substantial contact area in a two-ply, side-by-side relationship of the connected portions of the strip, and including a plurality 60 of individual band portions about the sausages and intervening readily severable web portions connecting said band portions.

OSCAR E. SEIFERTH.
